UNITED STATES PATENT OFFICE.

DLUAREJ N. JERAULD, OF EAST CLEVELAND, OHIO.

INK-VENDING DEVICE.

Application filed March 20, 1922. Serial No. 545,151.

To all whom it may concern:

Be it known that I, DLUAREJ N. JERAULD, a citizen of the United States, and a resident of East Cleveland, in the county of Cuyahoga and State of Ohio, have invented a new and useful Improvement in Ink-Vending Devices, of which the following is a full, clear, and exact description.

My invention relates to improvements in ink vending devices, and it consists in the combinations, constructions, and arrangements herein described and claimed.

An object of my invention is to provide an ink vending device which is coin controlled, and which is adapted to eject the desired amount of ink for the filling of a fountain pen or the like, during each operation thereof.

A further object of my invention is to provide a device of the character described which has a novel coin controlled mechanism.

A further object of my invention is to provide a device of the character described which has means for removing the stagnant ink in the well before a new supply is admitted to the well.

A further object of my invention is to provide a device of the character described which is relatively simple in construction, which is efficient for the purpose intended, and which is not likely to easily get out of order.

Other objects and advantages will appear in the following specification, and the novel features of the invention will be particularly pointed out in the appended claims.

My invention is illustrated in the accompanying drawings, forming part of this application, in which—

Figure 1 is a front elevation of the device portions thereof being shown in section,

Figure 2 is a section along the line 2—2 of Figure 1,

Figure 3 is a section along the line 3—3 of Figure 1,

Figure 4 is a rear elevation of the device, portions thereof being broken away,

Figure 5 is a section along the line 5—5 of Figure 1, and

Figure 6 is a plan view of a portion of the device.

In carrying out my invention, I provide a base 1 which has an upright portion 2 integral therewith. As clearly shown in Figures 1 and 2, the front portion of the up-

right 2 is designed so as to resemble a fountain pen, such as that indicated at 3. The portion 3 forms no part of my present invention, but merely aids as a selling feature to the device. The upright 2 also has a reservoir 4 therein, which is adapted to hold the ink. The top of the reservoir 4 is closed by a cap 5, and the bottom of the reservoir 4 is closed by a cylinder 6. It will be noted in Figure 2 that the cylinder 6 has an ink-receiving pocket 7 therein, this pocket being normally alined with the lower end of the reservoir 4, whereby the ink may flow from the reservoir into the pocket 7.

Positioned directly below the imitation pen point 8 is an ink-receiving receptacle 9 which is adapted to receive the ink ejected from the reservoir 4 by a means hereinafter described. A duct 10 terminates adjacent to the pen point 8, and communicates with the cylindrical opening 11 in which the cylinder 6 is disposed. It will be observed in Figure 2 that the duct 10 is of the same diameter as the pocket 7 so as to readily convey all of the ink from the pocket 7 when the pocket is rotated into alinement therewith. The ink will flow from the pocket 7 when the pocket is in alinement with the duct 10, and will pour from the end of the pen point 8 and drop into the receptacle 9, thus more or less resembling the ordinary flow of ink from the pen point of an ordinary fountain pen.

The means for controlling the movement of the cylinder 6 consists in a coin-receiving mechanism which is clearly shown in Figures 1, 3, 5, and 6. The upright 2 has a coin passageway 12 therein which is adapted to receive a coin in a horizontal position, and to swing the coin into a vertical position, whereby the coin will drop into a slot 13 in the cylinder 6, and into a slot 14 in a cylinder 15. In Figure 6 I have shown the slots 13 and 14 in alinement with each other, and it will be observed that the slots are deep enough so as to receive a coin 16 therein (see Figure 1). It will further be observed that the diameters of the cylinders 6 and 15 are the same as the coin 16 for a purpose hereinafter described. A plate 17 has a coin-receiving opening 18 therein, the plate being adapted to be moved inwardly so as to carry the opening 18 into registration with the passageway 12, whereby the coin in the opening 18 will drop through the passageway 12 and be guided into the

slots 13 and 14 in the cylinders 6 and 15. It will therefore be observed that the cylinders 6 and 15 are locked to each other, and a rotation of either of the cylinders will 5 rotate the other one. In other words, the coin 16 acts as a coupling means between the cylinders 6 and 15, and when no coin has been ejected into the device, either of the cylinders 6 or 15 may be rotated without 10 rotating the other cylinder. Both cylinders 6 and 15 are provided with torsional springs 19 and 20, the springs being adapted to return the cylinders 6 and 15 so as to position the slots 13 and 14 in alinement 15 with the bottom of the coin passageway 12 (see Figure 3). The cylinder 15 is further provided with a handle 21, which when swung, will rotate the cylinder 15. The cylinders 6 and 15 are further provided with 20 grooves 22 and 23, in which pins 24 and 25 are disposed, the pins being carried by the upright 2. The grooves 22 and 23 are long enough so as to determine the movement of the cylinders 6 and 15, respectively. The 25 groove 23 permits the cylinder 15 to be rotated so as to swing the slot 14 from alinement with the passageway 12 into alinement with a passageway 26, which in turn communicates with a coin-receiving box 27. 30 When a coin has been inserted between the cylinders 6 and 15 so as to operatively lock the two cylinders together, the ink pocket 7 will be swung into alinement with the duct 10 when the slot 14 is swung into alinement 35 with the passageway 26. In other words, the coin 16 is ejected from between the slots 13 and 14 and into the box 27 when the pocket 7 is in alinement with the duct 10. It will therefore be apparent that the ink 40 will be conveyed to the receptacle 9 at the same time as the coin will be conveyed to the box 27. As clearly shown in Figures 5 and 6, the adjacent ends of the cylinders 6 and 15 are disposed slightly apart so as 45 to permit a leaf spring 28 to slide between the cylinders. This spring is adapted to eject the coin from the slots 13 and 14 and into the box 27 when the slots have been brought into alinement with the passageway 26.

It is obvious that the ink deposited in the receptacle 9 is likely to be more than the fountain pen can hold, and therefore some of the ink will remain in the receptacle 9. 55 This ink would become coated with dust and thus be harmful if drawn into a fountain pen. To obviate this disadvantage, I dispose a cylinder 29 below the receptacle 9, the cylinder 29 having an ink passageway 30 therein which is normally in communication with the receptacle 9 (see Figure 1). The ink dropped into the receptacle 9 will therefore first fill the passageway 30 and then the receptacle. The passageway 30 is 60 preferably wide enough to receive the pen

point of an ordinary fountain pen. The cylinder 30 is operatively connected to the plate 17 so that when the plate 17 is actuated, the cylinder 29 will be rotated so as to bring the passageway 30 into alinement 70 with a passageway 31, the latter being in communication with an ink receiving box 32. It will therefore be apparent that the ink in the receptacle 9 will be conveyed to the box 32 before an additional quantity 75 of ink is ejected from the reservoir 4, since the plate 17 has to first be actuated before the cylinder 6 can be rotated. The means connecting the plate 17 with the cylinder 29 is clearly shown in Figure 4 and comprises a lever 33 which is connected to the plate 17 at 34, and which is connected to a link 35, the link in turn being connected to the arm 36 of the cylinder 29. A movement of the plate 17 inwardly to the dotted line position shown in Figure 4, will swing the cylinder 29 so as to aline the passageway 30 with the passageway 31. The plate 17 is brought back to normal position by 80 means of a spring 37.

From the foregoing description of the various parts of the device, the operation thereof may be readily understood. A person in desiring to fill his fountain pen, will place a coin in the opening 18 in the plate 17, and then manually move the plate 17 inwardly against the tension of the spring 37 so as to bring the opening 18 into alinement with the passageway 12. This same movement rotates the cylinder 29 so as to bring the passageway 30 into alinement with the passageway 31, as heretofore described, whereby the ink in the passageway 30 will be conveyed to the ink-receiving box 32. The coin will be dropped into the slots 13 and 14 in the cylinders 6 and 15, whereby the two cylinders are operatively connected to each other. The handle 21 may now be swung so as to rotate the cylinder 15, which in turn will rotate the cylinder 6. The movement of the handle 21 is determined by pins 38 which are carried by the side of the upright portion 22 (see Figure 1). When the handle 21 is swung to its furthest position, the slots 13 and 14 will be in alinement 95 with the passageway 26, and the pocket 7 will be in alinement with the duct 10. It will therefore be apparent that the ink in the pocket 7 will flow through the duct 10 and into the receptacle 9. It is obvious that the cylinder 6 acts as a stopper to the lower opening of the reservoir 4 when the pocket 7 is out of alinement with the reservoir. The coin 16 in the slots 13 and 14 will also be ejected into the box 27 by means of the spring 28, whereupon the spring 19 will instantly return the cylinder 6 to its normal position. As soon as the handle 21 is released, the spring 20 will return the cylinder 15 to its normal position. The cylinder 15 100

130

may now be swung without actuating the cylinder 6 until another coin is inserted in the device.

From the foregoing it will be apparent that the device cannot be actuated so as to eject a quantity of ink into the receptacle 9 until a coin 16 is inserted thereinto. As heretofore stated, the device is an advertising medium, since it resembles the ordinary fountain pen, and furthermore, causes the ink in the reservoir to pour from the imitation pen point 8 before it is conveyed to the receptacle 9. The device is novel in construction, and is efficient for the purpose intended.

I claim:

1. An ink vending device comprising an ink reservoir, an ink receiving receptacle, a passageway placing said reservoir in communication with said receptacle, a valve disposed in said passageway, an ink receiving compartment, a second passageway placing said receptacle in communication with said compartment, a valve disposed in said last named passageway, a lever means operatively connecting said lever to said second named valve, means for actuating said lever, said lever when actuated being adapted to

actuate said second named valve, and coin controlled means for actuating said first 30 named valve.

2. In an ink vending machine an ink receiving receptacle adapted to hold ink for the filling of fountain pens and the like, a compartment for receiving the waste ink 35 not used from the receptacle, a passageway between said receptacle and said compartment, a valve disposed in said passageway, means for conveying a coin into the machine, said means operatively connected to said 40 valve to actuate said valve when the coin is inserted into the machine.

3. In an ink vending machine, an ink reservoir, a receptacle adapted to receive ink, a passageway connecting said reservoir 45 with said receptacle, the lower end of said passageway being fashioned into a pen point, a coin controlled valve in said passageway, a compartment, a passageway leading from said receptacle to said compartment, a valve 50 disposed in said second named passageway, and means for conveying a coin into the machine, said means being arranged to actuate said second named valve.

DLUAREJ N. JERAULD.
